UNITED STATES PATENT OFFICE.

SAMUEL ARMSTRONG, OF NEWARK, NEW JERSEY, ASSIGNOR TO ANDREW D. CAMPBELL, OF SAME PLACE.

TOY REVOLVING DETONATOR.

SPECIFICATION forming part of Letters Patent No. 330,086, dated November 10, 1885.

Application filed March 7, 1885. Serial No. 158,008. (No model.)

To all whom it may concern:

Be it known that I, SAMUEL ARMSTRONG, a citizen of the United States, residing at Newark, in the county of Essex and State of New Jersey, have invented certain new and useful Improvements in Toy Revolving Detonators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The invention consists in the arrangements and combinations of parts, substantially as will be hereinafter set forth, and finally embodied in the clauses of the claim.

Referring to the accompanying two sheets of drawings, in which like letters of reference indicate corresponding parts in each of the several figures, Figure 1, Sheet 1, is a side elevation of a detonator having one of the body-plates removed to show the arrangements of interior parts. Fig. 2 is a plan of a revolving table or bed on which the caps are exploded. Fig. 3 is a side elevation similar to the first, showing the parts in position for firing, and Fig. 4 is a section of the device, taken through *x*, Fig. 1.

The figures of Sheet 2 illustrate a detonator of modified construction, Figs. 5 and 6 being side elevations showing the detonator with one of the side plates removed. Figs. 7 and 8 are detail views of a cap-receptacle as constructed for this second form of detonator. Fig. 9 is a horizontal section taken through line *x*, Fig. 6, and Fig. 10 is a vertical section through line *y*.

In said drawings, *a* indicates the body of the detonator, having a form or shape resembling an ordinary revolver. Of said body, *a'* is the handle, and *a''* the barrel. Upon within said body are formed or arranged a table, *b*, or bed, upon which the caps are exploded, also a suitable hammer, *c*, for exploding the cap, a trigger, *d*, for operating the hammer, a cap chamber or receptacle, *e*, and suitable mechanism for bringing the caps from the chamber *e* to a point in the line of path of the hammer automatically, and as often as the

hammer is "cocked" or raised prior to the exploding process.

The construction preferred is shown on Sheet 1 of the drawings. I here show a revolving table or bed, the upper surface of which extends from beneath the cap-receptacle to a position in the path of the hammer *c*, so that the movement of the bed may carry a cap or charge from said receptacle to a point where it may be exploded. Said bed or table may be operated by any suitable mechanism; but I prefer to form or construct a series of ratchet-teeth, *f*, thereon, to be engaged by a suitable pawl, *g*, connected with the hammer in such a manner as to operate the table or bed when the hammer is cocked. In said preferred construction the hammer is pivoted on a pin or journal, *h*, and is provided with an arm, *i*, which is connected with the pawl, throwing the same forward when the hammer is raised. The spring *j* holds the hammer in an upright position, and when the trigger is pulled gives impetus to its downward movement. The spring *k*, fastened at one end to the handle, passes into a perforation or recess in the trigger and tends to hold the same forward. After the hammer is cocked, prior to exploding the cap, the trigger, which is pivoted on the journal with the hammer, is pulled, when a projection, *l*, of said trigger engages a cooperating projection, *m*, of the hammer, and forces the spring-bearing thereof past the center line, enabling said spring to act in exploding the cap, as will be understood. The top of the table or bed *b*, in the construction now being specifically described, is provided with a series of recesses, *n*, Figs. 2 and 3, of a diameter and depth approximately equal to that of the cap. Said recesses are caused to successively coincide with the receptacle by the pawl *g*, one movement of which is sufficient to throw the table from one recess to the next in the series. The cap-receptacle is tubular or cylindrical, so as to receive a pile of overlying caps, the size of the cylinder being about equal to the size of the caps now found in the market. By means of a spring or weight, *e'*, at the top of the receptacle the caps are forced or borne down into the recesses of the table or bed one at a time, the number being limited by the size of said recesses.

The caps are then carried or conveyed to the hammer. As a matter of convenience, I prefer to have four recesses in the series, which when the table is at rest in the firing process 5 are disposed one beneath the receptacle, with a cap therein, one midway between said receptacle and the hammer, having an uncovered cap therein, one beneath the hammer, and the remaining one, from which the cap has been 10 emptied by consumption in the explosion, opposite the second. When employing the four said recesses, I may provide a spring, *o*, which bears on the top of the table over the recess containing the uncovered cap, so that 15 when a blow is struck by the hammer *c* the cap will not be thrown from said recess. I also provide a spring, *p*, to bear against the said table to produce sufficient friction to overcome the force of inertia, so that the recesses will not be thrown past the mouth or bottom opening in the receptacle when pushed by the pawl. The two springs *o* and *p* are 20 preferably made of one continuous piece of wire formed and arranged as shown.

25 The receptacle may be provided with a cover or lid, *q*, as in Fig. 3.

It will be evident upon inspection of Figs. 5 to 10 that considerable change may be made in the construction of the operative parts 30 without departing from the spirit of the invention.

In lieu of a movable table or bed upon which to explode the cap, I may employ a fixed one, as *b'*, the cap *s* being carried to or pushed 35 upon said bed by a finger, *t*, working through a slot, *u*, in the bottom of the receptacle operated by a system of levers connecting with the hammer, or by other mechanism.

In operating the device the hammer is 40 raised by the operator's hand, which act causes a cap to be deposited automatically on the bed, either in a position for exploding or to be then turned or otherwise brought to a position for exploding.

45 I am aware that a detonator has been constructed to explode charges of fulminating substances disposed at intervals on a continuous ribbon.

50 My device is intended to explode caps or papers detached from one another each containing or bearing a single charge.

What I claim as new is—

1. In combination, a body, *a*, bed *b*, hammer *c*, trigger *d*, an immovable cap-receptacle, *e*, fixed stationary upon the body *a*, and mechanism, substantially as described, adapted to automatically carry the cap from said receptacle to a point upon said bed in a position to receive the blow of the hammer.
- 60 2. In a detonator having a receptacle and hammer, a table extending from said receptacle to said hammer, and having a series of

shallow depressions or recesses in the face thereof to receive a series of detached caps, said table being movable to carry or convey 65 the said caps from said receptacle to said hammer, substantially as set forth.

3. In combination, the body *a*, tubular receptacle *e*, having an open bottom, a recessed table extending from said receptacle to the hammer, and adapted to receive and hold a series of caps as they drop or are forced automatically through said open bottom from the tubular receptacle, said hammer pivoted on the body, a trigger, springs *j* *k*, and means for 70 revolving the table automatically when the hammer is raised, substantially as set forth.

4. In a detonator, a tubular receptacle adapted to hold a pile or columnar succession of caps, a flat bed upon which to explode 80 said caps, a hammer for exploding said caps, and mechanism, substantially as described, adapted to transfer caps from the receptacle to the bed automatically when the said hammer is raised.

85 5. In combination, in a detonator, a body, *a*, having a receptacle for a succession or pile of caps, said receptacle having an open bottom, and mechanism, substantially such as described, for pressing said caps toward said open bottom, substantially as and for the purpose set forth.

6. In a detonator, a body, *a*, a receptacle *e*, fixed upon said body *a*, to receive a pile or succession of caps, a hammer to explode said 95 caps, a movable bed upon which to explode said caps, and mechanism, substantially such as described, for transferring the caps one by one from the bottom of said pile to a point on said bed in line with the hammer, substantially as and for the purposes set forth.

7. In a detonator, the combination of a body, *a*, a revolving bed having a series of shallow cap-recesses in the face thereof, and a spring-arm, *o*, secured on said body and extending across one of said recesses, to hold the cap therein while a cap in another is being exploded, substantially as shown and described.

8. In a revolving detonator, the combination, with the body, of a tubular cap-receptacle adapted to receive a succession or pile of caps, and having an open bottom to allow the exit of said caps, and a weight or its equivalent to force said caps down through said opening, as set forth.

In testimony that I claim the foregoing I have hereunto set my hand, this 27th day of January, 1885.

SAMUEL ARMSTRONG.
